UNITED STATES PATENT OFFICE.

CHARLES A. KRAUS AND CONRAD C. CALLIS, OF WORCESTER, MASSACHUSETTS, AS
SIGNORS TO STANDARD DEVELOPMENT COMPANY, A CORPORATION OF DELA-
WARE.

ART OF MAKING METALLO-ORGANIC COMPOUNDS.

No Drawing.

Application filed April 13, 1923. Serial No. 631,940.

This invention relates to the art of making metalloc-organic compounds, and will be fully understood from the following description:

5 In the preparation of hydrocarbon compounds of metals heretofore the methods followed have been based upon the action of iodids, or unstable compounds of zinc, etc. These methods have been characterized 10 by high cost and uncertain yields, and attended with various operating difficulties. In the experiments recorded in the literature, where alloys containing sodium have 15 been used pressure has been avoided, the alloy being heated with an alkyl iodid under a reflux condenser (Lowig, Annalen d. Chem. 84, 308; Lowig, Jour. Prak. Chem. 60, 304; Klippel, Jour. Prak. Chem. 81, 287; Ladenburg, Ann. d. Chem. Supplement 8, 20 75, 78).

In proceeding in accordance with the present invention, the metal to be used, is, in advantageous condition for reaction, (as for instance in alloy with a highly electro-positive metal, as an alkali metal or alkaline earth metal), subjected to a reagent involving a direct transfer of hydrocarbon radicals, as more particularly pointed out hereinafter. In the case of a metal of the 25 second sub-group of the fourth periodic group, (tin, lead, germanium), sodium for instance is preferably employed as the alloy ingredient. For brevity, the metals mentioned will be referred to herein as metals of 30 the tin sub-group.

As an example, tin in the proportion of 80—94% is suitably alloyed with sodium in the complementary proportions of 20—6%, (preferably 86% of tin and 14% of sodium, 40 corresponding to the formula Na_2Sn), and the alloy is subdivided to suitable size, as for instance about the size of wheat grains, and introduced into a reaction vessel capable of 45 withstanding pressure, and equipped with suitable heating and cooling means, as a jacket or coils, also stirring means, so as to afford a close temperature control, as it is desired that local rises or irregularities in

temperature should not occur. The vessel may be mounted for rotation and contain 50 balls or the like in the manner of a ball mill.

Methyl chlorid being introduced into the reaction vessel in suitable amount (before or after the introduction of the alloy, as desired), and the alloy being suitably subdivided, the reaction is ready to proceed. Ordinarily, to start the reaction, slight warming, say up to about 30° C. is desirable, but after the reaction is well under way, 60 more or less cooling is ordinarily required. By the use of a closed, pressure-resistant vessel, the methyl chlorid, although low-boiling, can be held under pressure, and at the said temperature or slightly above, to 65 about 50° C., and finally when well toward the end, even as high as 100° C. On completion of the reaction, which requires about 70 2-24 hours, depending upon the conditions, practically pure tin tetramethyl can be taken off.

Instead of methyl chlorid, other desired alkyl chlorids or bromids can be employed; for instance ethyl chlorid or ethyl bromid may be used and the corresponding tin 75 tetraethyl obtained.

If desired, a catalyst may be employed, as for example zinc. In using the zinc, this, to the amount of about 0.5 to 3% may conveniently be initially alloyed with the tin and sodium. The use of a catalyst promotes the reaction of the alkyl halid, and particularly where the sodium or the like is not in molecular proportion with the tin or lead.

In general, in order to facilitate the reaction, it is desirable to employ more than the calculated molecular equivalent of the methyl chlorid or other hydrocarbon halid used. In such case, after completion of the reaction, the excess may be recovered, as by distilling off, or it may be advantageous to use an exhaust pump. The methyl chlorid so recovered is condensed or re-compressed and condensed and may be employed in subsequent reactions. The surplus methyl chlorid having been removed, the reaction

vessel is cooled and water may be introduced. Steam may also be bubbled in through suitable pipes in the vessel and the tin tetramethyl reaction product is distilled out and

5 condensed, and collected in a suitable receiver. The tin tetramethyl being insoluble in and heavier than water, may be readily drawn off and separated from water of condensation, and a final filtration and drying 10 may be carried out if desired. In the case of the lower boiling organic tin compounds, the desired product may, if preferred, be removed from the reaction vessel by ordinary distillation.

15 The residue in the reaction vessel contains tin and sodium chlorid. By repeated leaching and washing with water, the sodium chlorid may be removed, and the tin in divided condition may be dried and after 20 alloying be used for subsequent reactions.

Instead of tin as in the illustration detailed, other metals, as for example lead, may be employed, and the corresponding metallo-organic compound obtained. While 25 the invention is directed especially to the production of compounds in which all the valences of the metal are satisfied by hydrocarbon groups, such as tin tetramethyl, lead tetraethyl etc., it is also applicable for the 30 preparation of compounds in which only a portion of the valences of the metallic atom are satisfied with hydrocarbon radicals.

While the invention has been described by reference to certain specific details, it will be 35 understood that this is for the purpose of illustration and is not limitative; and changes may be made which come within the spirit and scope of the invention.

What we claim is:

40 1. The improvement in the art of making tin tetramethyl, which comprises alloying tin with sodium in the proportions of about 86% of tin and 14% of sodium, subdividing the alloy, and reacting upon the alloy with 45 methyl chlorid under pressure at a temperature between about 30° and 100° C. in the presence of zinc as a catalyst.

2. The improvement in the art of making 50 tin tetramethyl, which comprises alloying tin with sodium, subdividing the alloy and reacting upon the alloy with methyl chlorid while maintaining the temperature above the normal boiling point of methyl chlorid.

3. The improvement in the art of making 55 hydrocarbon compounds of metals of the tin sub-group, which comprises alloying the metal with sodium, sub-dividing the alloy and reacting upon the alloy with an alkyl chlorid in the presence of a catalyst, while maintaining the temperature above the normal boiling point of the alkyl chlorid.

4. The improvement in the art of making 60 metallo-alkyl compounds of metals of the tin sub-group, which comprises alloying the metal with sodium, and reacting upon the

alloy with an alkyl halid in which the halogen has a lower atomic weight than iodin, while maintaining a pressure above normal atmospheric pressure.

5. The improvement in the art of making 70 metallo-alkyl compounds of metals of the tin sub-group, which comprises alloying the metal with sodium, and reacting upon the alloy with an alkyl chlorid while maintaining a temperature above the normal boiling 75 point of the alkyl chlorid.

6. The improvement in the art of making 80 metallo-alkyl compounds of metals of the tin sub-group, which comprises alloying the metal with sodium, and reacting upon the alloy with an alkyl halid in which the halogen has a lower atomic weight than iodin. in the presence of a catalyst while maintaining a temperature above the normal 85 boiling point of the alkyl halid.

7. The improvement in the art of making 90 metallo-alkyl compounds of metals of the tin sub-group, which comprises subjecting the metal in alloy with sodium to the action of an alkyl halid whose halogen is of a lower atomic weight than iodin, in the presence of a catalyst while maintaining a temperature above the normal boiling point of the alkyl halid.

8. The improvement in the art of making 95 metallo-alkyl compounds of metals of the tin sub-group, which comprises subjecting the metal in alloy with a highly electro-positive metal to the action of an alkyl halid in which the halogen has a lower atomic 100 weight than iodin, in the presence of a catalyst while maintaining a pressure above normal atmospheric pressure.

9. The improvement in the art of making 105 metallo-alkyl compounds of metals of the tin sub-group, which comprises subjecting the metal in alloy with a highly electro-positive metal to the action of an alkyl halid in which the halogen has a lower atomic 110 weight than iodin, in the presence of a catalyst while maintaining a temperature above the normal boiling point of the alkyl halid.

10. The improvement in the art of making 115 metallo-alkyl compounds of metals of the tin sub-group, which comprises subjecting the metal in alloy with an alkali metal to the action of an alkyl halid whose halogen is of lower atomic weight than iodin and in the presence of a catalyst.

11. The improvement in the art of making 120 metallo-alkyl compounds of metals of the tin sub-group, which comprises subjecting the metal in alloy with an alkali metal to the action of an alkyl halid whose halogen is of lower atomic weight than iodin while maintained a pressure above normal atmospheric pressure.

12. The improvement in the art of making 125 metallo-alkyl compounds of metals of the

tin sub-group, which comprises subjecting the metal in alloy with an alkali metal to the action of an alkyl halid whose halogen is of lower atomic weight than iodin while maintaining a temperature above the normal boiling point of the alkyl halid.

13. The improvement in the art of making

metallo-alkyl compounds of metals of the tin sub-group, which comprises subjecting the metal in alloy with an alkali metal to the action of an alkyl halid whose halogen is of lower atomic weight than iodin. 10
